UNITED STATES PATENT OFFICE.

RUDOLPH CONRADER, OF ERIE, PENNSYLVANIA.

PUMP.

1,178,218.

Specification of Letters Patent.

Patented Apr. 4, 1916.

Application filed March 30, 1914. Serial No. 828,145.

To all whom it may concern:

Be it known that I, RUDOLPH CONRADER, a citizen of the United States, residing at Erie, in the county of Erie and State of Pennsylvania, have invented new and useful Improvements in Pumps, of which the following is a specification.

This invention relates to pumps and consists in certain improvements in the construction thereof as will be hereinafter fully described and pointed out in the claims.

The object of the invention is to provide such a pump ordinarily used in deep wells such as oil wells with a standing valve which is tight under normal conditions but which may be readily pulled when desired.

The invention is illustrated in the accompanying drawings as follows:—

Figure 1 shows a central section of the pump. Fig. 2 a section on the line 2—2 in Fig. 1. Fig. 3 a section on the line 3—3 in Fig. 1. Fig. 4 a section on the line 4—4 in Fig. 1. Fig. 5 a section on the line 5—5 in Fig. 1.

1 marks the working barrel, 2 the coupling at the bottom of the working barrel, and 3 the strainer tube which is secured to the seat coupling 2. The coupling 2 has a seat for the standing valve. This seat is beveled and this is of common construction. The standing valve seat is beveled to correspond to the bevel of the seat 4. A hexagon 6 extends below the seat 5 and the screw thread 7 is provided in the hexagon.

As ordinarily constructed standing valves are arranged in the manner so far described with the seat 5 and the coupling 4, but the seat 5 has portions of it commonly flattened forming a wrench hold for assembling the parts of the standing valve. This reduces the contact surfaces so that leakage is not always prevented. With this device the wrench hold is arranged below the seat so that there is a full contact surface of the seat.

A standing valve tube 8 is screwed into the seat piece 5. It has a shoulder 9 on its upper end. An upwardly extending cup is arranged below this shoulder and flexible rings 11 and 12, ordinarily formed of leather are arranged below the cup 10. A distance piece 13 is arranged below the ring 12 and a cup 14 is arranged below the distance piece 13. The seat piece has the extension 5*

which forms a seat for the lower cup, the seat piece being concave so as to fully support the cup.

By forming the rings 11 and 12 of slightly greater diameter normally than the working barrel they are bent up slightly at the edges when the standing valve is forced to place, the turn of the cup 10 permitting this upturning of the edge of the ring. This forms a gripping surface which prevents the upward movement of the standing valve under the normal pumping action of the pump, yet the rings are of such size as to readily permit of the reversing of the turn when sufficient pressure is put on the standing valve to pull it.

It will be noted that the extension 5^a carries the lower cup 14 above the bottom edge of the pump barrel. In ordinary practice, the bottom of the pump barrel was not screwed down to the seat 4 of the coupling 2 so that there is a small space left below the end of the barrel and where rings are used for packing the standing valve they swell into this space and are stripped when the standing valve is lifted. The upper end of the sleeve 8 has a screw threaded portion 15 on which the cage 16 is screwed, the standing valve seat being secured by the cage.

18 marks the ball of the standing valve, 19 the pump plunger and 20 the ball check of the plunger.

The plunger is provided with the cups 22 which are clamped in position by the plunger end 21. The plunger end has the lips 23 with the perforation 24. A screw 25 extends through the perforation. It is provided with the head 26. The extension 27 extends through the bar 28 in the plunger end 21. A spring 29 yieldingly forces the screw to its downward position. The screw is adapted to enter the screw threaded portion 30 in the upper end of the cage 16.

When it is desired to lift the standing valve, the plunger is lowered bringing the screw 25 into position to enter the screw threaded perforation 30. By turning the plunger, the screw 25 is screwed into the perforation thus connecting the standing valve with the plunger. The jar in lifting the plunger will readily release the washers 11 and 12 so that there will be no tendency to strip any parts of the standing valve as it is being lifted. At the same time, the wash-

ers 11 and 12 prevent the displacement of the standing valve under pressure due to the pulsations of the pump.

I do not claim in this application the specific structure of plunger herein shown and described and this forms the subject matter of a separate application filed on even date with this application #828,144.

What I claim as new is:—

- 10 1. In a pump, the combination of a barrel; a seat coupling on the barrel; a standing valve; a cup on the standing valve forming a joint with the barrel; and a flexible washer forming a joint between the stand-
- 15 ing valve and the barrel, said washer being larger than the bore of the barrel but reversible on the pulling of the standing valve.
- 20 2. In a pump, the combination of a barrel; a seat coupling on the barrel; a standing valve; a cup on the standing valve; and a plurality of flexible washers forming a joint with the barrel, said washers being larger than the bore of the barrel but reversible on the pulling of the standing valve.
- 25 3. In a pump, the combination of a barrel; a seat coupling on the barrel; a standing valve; a cup on the standing valve forming a joint with the barrel; and a washer arranged below the cup and constructed to lock the standing valve in place in the barrel.
- 30 4. In a pump, the combination of a barrel; a seat coupling on the barrel; a standing valve; a cup on the standing valve forming

a joint with the barrel; and a flexible washer constructed to lock the standing valve with the barrel when subjected to normal pressure.

5. In a pump, the combination of a barrel; a seat coupling on the barrel; a standing valve; a cup forming a joint between the standing valve and the barrel; a flexible washer arranged below the cup and constructed to lock the standing valve in the barrel; a distance piece below the washer; a cup below the distance piece; and a seat piece clamping the cups and washer on the standing valve.

6. In a pump, the combination of a barrel; a seat coupling on the barrel; a standing valve; a cup forming a joint between the standing valve and the barrel; a flexible washer arranged below the cup and constructed to lock the standing valve in the barrel; a distance piece below the washer; a cup below the distance piece; and a seat piece clamping the cups and washer on the standing valve, said seat piece having an extension carrying the bottom of the lowest cup above the bottom of the barrel.

In testimony whereof I have hereunto set my hand in the presence of two subscribing witnesses.

RUDOLPH CONRADER.
